UNITED STATES PATENT OFFICE.

PHILIP W. McABEE, OF MUNCIE, INDIANA.

DESIGN FOR A BOTTLE.

Application filed September 8, 1925. Serial No. 14,721. Term of patent 14 years.

To all whom it may concern:

Be it known that I, PHILIP W. McABEE, a citizen of the United States, residing at Muncie, in the county of Delaware and State of Indiana, have invented a new, original, and ornamental Design for Bottles, of which the following is a specification, reference being had to the accompanying drawing, forming a part thereof.

In the drawing, the figure is a perspective view of a bottle showing my design.

I claim:

The ornamental design for a bottle as shown.

In witness whereof, I PHILIP W. McABEE have hereunto set my hand at Muncie, Indiana, this 15th day of August, A. D., one thousand nine hundred and twenty-five.

PHILIP W. McABEE.
